UNITED STATES PATENT OFFICE.

PAUL L. VARBLE, OF CARROLLTON, ILLINOIS.

CONNECTOR.

Application filed June 1, 1921. Serial No. 474,162.

To all whom it may concern:

Be it known that I, PAUL L. VARBLE, a citizen of the United States, residing at Carrollton, in the county of Greene and State of Illinois, have invented certain new and useful Improvements in Connectors, of which the following is a specification, reference being had to the accompanying drawings.

This invention relates to certain improvements in connectors and has relation more particularly to a device of this general character especially designed and adapted for use in connection with terminals of various members such as non skid chains for tires and the like, and it is an object of the invention to provide a device of this general character having novel and improved means whereby the tension created by the members with which the connector is employed serves

20 to maintain the same in working position.

Another object of the invention is to provide a novel and improved device of this character comprising two members connected together for relative swinging movement, 25 each of said members being provided with means for engagement with the terminal of the member, the pivotal connection between the members being to one side of the center of tension imposed upon the device by the 30 members to which the connector is applied:

Furthermore it is an object of the invention to provide a novel and improved device of this general character comprising two members associated in a manner whereby 35 the pull imposed thereon when the device is in applied position continues to maintain the members of the device in closed or working relation and wherein said members are so constructed to be effectively protected 40 against interference by mud or other foreign matter.

The invention consists in the details of construction and in the combination and arrangement of the several parts of my improved connector whereby certain important advantages are attained and the device rendered simpler, less expensive and otherwise more convenient and advantageous for use, as will be hereinafter more fully set forth.

50 The novel features of my invention will hereinafter be definitely claimed.

In order that my invention may be the better understood, I will now proceed to describe the same with reference to the accompanying drawings, wherein:

Figure 1 is a view in side elevation illus-

trating a connector constructed in accordance with an embodiment of my invention and in working adjustment,

Figure 2 is a sectional view taken substantially on the line 2—2 of Figure 1.

Figure 3 is a view in side elevation of the device herein embodied with the members in open or separated relation.

Figure 4 is a view in bottom plan of the 65 device as illustrated in Figure 3, and

Figure 5 is a view in side elevation showing the members in partly folded or compacted relation.

Figure 6 is a sectional view through the 70 connector at a point through the pinched end 3 of the keeper, showing how the lever may be engaged between the sides of the keeper to raise the keeper from its closed position.

75 My improved device as herein disclosed, comprises two members, A and B, the member A constituting a female member and the member B constituting a male member. The member A comprises a pair of spaced side 80 plates 1 having similar or top edges integrally connected, as at 2, by an intermediate web, said web connecting the central portion of the plates 1. The marginal portions of the plates 1 outwardly at one end of the 85 connecting web 2 are pressed together, as at 3, to provide a portion adapted to be gripped by a pair of pliers or other suitable implement to facilitate the relative movement of the members A and B. Each of the side 90 plates 1 of the member A is provided with a substantially arcuate slot 4, the slot of one plate being substantially in register or coincidence with the slot of the second plate. The slot 4 is substantially entirely to one 95 side of the pivotal connection 5 between the members A and B, as will hereinafter be more particularly referred to, and the bow of said slot extends inwardly of the plate.

100 Each of the plates 1 in its free longitudinal marginal portion is provided with an entrance opening or slot 6 in communication with the slot 4 of the plate, said slot 6 as herein disclosed being in relative close proximity to the end of the slot 4 remote from the pivotal connection 5. The slots 6 of the plates 1 are also substantially in register or coincidence.

105 The male member B is of a length greater than the length of the female member A and said member B is adapted to snugly fit between the plates 1 of the member A. The

members A and B adjacent similar ends are pivotally connected at 5, as hereinbefore referred to, said connection being to one side of the transverse center of the members A and B or the center of tension and also substantially beyond the slots 4 in the plates 1 of the member A and toward the side of the plates 1 which are connected by the interposed web 2.

10 The member B is of such length as to have an end portion extend beyond the end portion of the member A remote from the pivotal connection 5 when the members A and B are in folded or compacted relation, said 15 extended end portions being reduced in width by transversely grooving the member B in order to compensate for the pressed portion 3 of the plates 1 and to permit the insertion of a lever between the portion 3 of 20 the member A and the member B to force the members open.

In the present embodiment of my invention, the free or extended end portion of the member B has pivoted, or otherwise engaged 25 therewith, as at 7, a terminal portion of a side chain 8 of a nonskid device for tires or the like, although I do not wish to be understood as limiting myself to the use of my improved connector with this particular element, as my invention can be employed with 30 equal facility in connection with the terminal of a tug or trace member or in connection with the top of an automobile and various other usages.

35 The pivoted end portion of the member B adjacent the pivotal connection 5 is provided with an open end arcuate or kindred slot 9 having the connection 5 as a center. This slot 9 is open at the side marginal portion 40 of the member B adjacent the pivotal connection 5 and said slot extends inwardly of the member B and toward the pivoted end portion thereof with the closed end of said slot terminating at the side of the trans- 45 verse center of the member B remote from the pivotal connection 5, such closed ends forming a cove for the reception of a link or loop 10.

In practice, when it is desired to effect a 50 connection, the member A is swung outwardly with respect to the member B whereupon the link or loop 10 of the opposite end portion of the side chain 8 is then swung inwardly of and toward the member B 55 which draws the second terminal inwardly of the member A, placing the side chain 8 or other member or members under tension. As the member A swings inwardly toward the member B, the link or loop 10 moves to 60 the lower or inner end portion of the slots 4 so that after the member A has been swung inwardly substantially one-fourth of its in-

ward swinging movement, the tension of the side chain 8 or other member or members will automatically cause the member A, under the influence of the tension of the chain 8 or other member or members, to swing inwardly the remainder of the distance and during which movement the link or loop 10 is received within the slot 9 whereby the 70 terminals of the chain 8 or other member or members are effectively coupled and maintained in such relation. It is to be particularly noted that the greater the pull or tension upon the members A and B, the more 75 effective the connecting or coupling functioning of my improved device.

It will also be particularly noted by having the member A snugly engaging between the plates 1 of the member B, interference 80 with the requisite working of my improved device by mud or other foreign matter is practically eliminated.

From the foregoing description it is thought to be obvious that a connector constructed in accordance with my invention is particularly well adapted for use by reason of the convenience and facility with which it may be assembled and operated, and it will also be obvious that my invention is 90 susceptible of some change and modification without departing from the principles and spirit thereof and for this reason I do not wish to be understood as limiting myself to the precise arrangement and formation of 95 the several parts herein shown in carrying out my invention in practice except as hereinafter claimed.

I claim:

1. In a chain fastener, a connecting plate 100 having a link receiving slot therein and a groove adjacent the mouth of said slot, and a keeper pivoted to said connecting plate and adapted to close the mouth of said slot, said keeper including spaced walls, 105 portions of which are pressed together at the free end of the keeper, said portions being positioned above said groove when the keeper is in closed position and providing means to be gripped by pliers for causing 110 opening movement of the keeper relative to the plate.

2. In a chain fastener, a connecting plate 115 having a link receiving slot therein, and a keeper pivoted to said connecting plate and adapted to close the mouth of said slot, said keeper including spaced walls, portions of which are pressed together at the free end of the keeper to provide means to be gripped by pliers or the like for causing opening 120 movement of the keeper relative to the plate.

In testimony whereof I hereunto affix my signature.

PAUL L. VARBLE.
